UNITED STATES PATENT OFFICE.

LAURENCE J. BERKELEY, OF RACINE, WISCONSIN, ASSIGNOR TO THE P. & M. COMPANY, OF CHICAGO, ILLINOIS, A CORPORATION OF ILLINOIS.

RAIL-ANCHOR.

1,356,688.

Specification of Letters Patent. Patented Oct. 26, 1920.

Application filed January 3, 1919. Serial No. 269,414.

To all whom it may concern:

Be it known that I, LAURENCE J. BERKELEY, a citizen of the United States, residing at Racine, in the county of Racine and State of Wisconsin, have invented a new and useful Improvement in Rail-Anchors, of which the following is a full, clear, and exact description, reference being had to the accompanying drawings, forming part of this specification, in which—

Figure 1 is a transverse vertical section showing a rail anchor embodying my invention applied to a rail.

Fig. 2 is a plan view of the same with the rail in dotted lines and the rail tie partly broken away.

Fig. 3 is a transverse section of a modified form of anchor applied to a rail.

Fig. 4 is a perspective view of the anchor shown in Fig. 3, and

Fig. 5 is a detail sectional view of the anchor.

My invention has relation to rail anchors and is designed to provide a device of this character which is simple in its construction and mode of operation; which will effectively prevent creeping of the rails; and which is of such character that when removed after a period of service, it can be readily reused.

The nature of my invention will be best understood by reference to the accompanying drawings in which I have shown two different forms of my invention and which will now be described, it being premised, however, that various changes can be made in the details of construction, arrangement and combination of the parts within the spirit and scope of the appended claims.

Referring first to that form of my invention shown in Figs. 1 and 2, the numeral 2 designates a track rail to which I have shown the rail anchor applied, and 3 one of the track ties.

The anchor consists of a base portion 4 of narrow plate form having upwardly extending flanges 5 and 6 at its respective ends. The flange 5 is formed with an inner approximately vertical rail engaging face 7, the upper end portion 8 of the flange being lipped over inwardly to engage the rail base. The other flange 6 is higher than the flange 5 and is provided with the approximately vertical rail engaging face 9, and 55 with the lip 10 at the upper end of the same.

The lower portion of the flange, below the face 9, is recessed laterally outward, as shown at 11. This recessing extends sufficiently beyond the face 9 to permit the anchor to be readily applied to the base of a 60 rail as shown in Fig. 2, the distance between the outer wall of said recess and the face 7 of the opposite flange being greater than the transverse width of the rail base. After the anchor has been applied to the rail so 65 that one of the flanges of the rail base extends into the recess 11, the anchor is moved laterally (to the right looking at Fig. 1) and is then moved so as to bring the opposite edge of the rail base into contact with 70 the face 9. When the anchor is in this position, any creeping of the rail toward the tie will cause the anchor to be skewed on the rail base so that the edge of the face 9 nearest the tie and the edge of the face 7 75 farthest from the tie will be forced into biting engagement with the vertical edges of the rail base.

12 is a leaf-spring which is secured at one end of the base portion 4 and which is 80 adapted to bear upwardly against the underside of the rail base, thus holding the parts in the position shown in Fig. 1. The base portion 4 is recessed as shown at 13 so that in applying the anchor to the rail, 85 the spring may be pressed back flush with the general level of the surface of the base.

14 designates a tie engaging lug or "pad" which bears against one side of the tie 3 at a point adjacent the edge of the rail. 90

It will be noted that the rail is very securely gripped by its edges and that any tendency of the rail to creep endwise in the direction of travel thereon will act to tighten the grip. It will further be noted 95 that no effort is made in my improved anchor to secure a top and bottom grip upon the surfaces of the rail base, but that the gripping is solely at the edges of such base. Where reliance is placed upon top and bottom grips the action is not satisfactory, owing to the very considerable variations which occur in the thickness of the edge portions of rail bases. Furthermore, the action which occurs with such devices tends to 100 distort the gripping jaws so that when the anchor has once been removed from a rail it is usually useless for further service. There is comparatively little variation in the width of the rail bases, and such slight 110

variations as may occur are readily taken care of with my anchor by a slightly decreased or increased skew position of the anchor. When the anchor is removed from the rail, it is uninjured and can be readily used over again.

In Figs. 3 and 4 I have shown a modification in my invention which is, in some respects, preferable. The anchor is substantially the same as that shown in Figs. 1 and 2, except that it normally stands diagonally across the rail base at a greater angle than illustrated in Fig. 2 and I provide the rail bearing face 9^a of the flange 6^a with an inwardly extending bottom lip 9^b, so that the gripping face 9^a is between this lip and the top lip 10^a. Here again no attempt is made to secure a binding grip of the rail between these two lips, the lower lip 9^b being provided solely for the purpose of preventing the lifting of the anchor by the tampering of ballast thereunder. The action is the same otherwise as with the form first described—that is, the edge of the jaw 5^a farthest away from the tie and the edge of the face 9^a nearest the tie take a biting hold on the rail base during any creeping action of the rail.

In applying this form of rail anchor, one flange of the rail base is inserted into the recess 11^a so as to permit the lip 8^a to clear the opposite edge of the rail. The anchor is then moved to the right (looking at Fig. 3) until the lip 8^a, at the left of the anchor, extends the desired distance over the upper edge of the rail base. The end of the anchor at the right of Fig. 3 is then skewed in a direction away from the tie until the lip 9^b clears the edge of the rail. This end of the anchor is then lowered and skewed in a direction toward the tie until the edge of the face 9^a nearest the tie engages the vertical edge of the rail base.

I claim:

1. A rail anchor comprising a base portion formed with an upwardly extending flange at each end, each of said flanges having an approximately vertical rail gripping inner face, said faces being at different heights from the top of the base and adapted to engage the rail at points longitudinally remote from each other, whereby the gripping may be effected by horizontally skewing the anchor, and a spring seated on said base portion and arranged to bear upwardly against the underside of the base of a rail, substantially as described.

2. A rail anchor comprising a base portion formed with an upwardly extending flange at each end, each of said flanges having an approximately vertical rail gripping inner face, said faces being at different heights from the top of the base and adapted to engage the rail at points longitudinally remote from each other, whereby the

gripping may be effected by horizontally skewing the anchor, and a spring seated on said base portion and arranged to bear upwardly against the underside of the base of a rail to hold the anchor in its skewed 70 position.

3. A rail anchor comprising a base portion formed with an upwardly extending flange at each end, each of said flanges having an approximately vertical rail gripping 75 inner face, and a spring seated on said base portion and arranged to bear upwardly against the underside of the base of a rail, said rail gripping faces being at different heights from said base and the flange having 80 the higher grip face being recessed below and laterally beyond said face, substantially as described.

4. A rail anchor comprising a base portion, formed with an upwardly extending 85 flange at each end, said flanges being of different heights, each flange having an inner approximately vertical rail gripping face, and the higher flange being recessed laterally below and beyond said face, said base 90 and flanges being substantially rigid and arranged to grip a rail base by skewing the anchor horizontally, substantially as described.

5. A rail anchor comprising a base portion, formed with an upwardly extending flange at each end, said flanges being of different heights, each flange having an inner approximately vertical rail gripping face and the higher flange being recessed laterally below and beyond said face, together 100 with a spring seated on said base portion and arranged to bear upwardly against the base of a rail, substantially as described.

6. A rail anchor, comprising a base portion formed with an upwardly extending flange at each end, said flanges being of different heights, each flange having an inner approximately vertical rail gripping face and the higher flange being recessed laterally below and beyond said face, together 110 with a spring seated on said base portion and arranged to bear upwardly against the base of a rail, and the base portion having a recess to receive said spring, substantially 115 as described.

7. A rail anchor, comprising a base portion formed with an upwardly extending flange at each end, each of said flanges having an approximately vertical rail gripping 120 face, said faces being at different heights from said base, and there being an inwardly projecting lip at the lower end of one of said faces, said base and flanges being substantially rigid and arranged to grip a rail base 125 by skewing the anchor horizontally, substantially as described.

8. A rail anchor, comprising a base portion having an upwardly extending flange at each end, each of said flanges having an 130

- approximately vertical rail gripping face, the two rail gripping faces being at different heights from said base, and each of said flanges terminating at its upper end above 5 the rail gripping face in an inwardly projecting lip, said base and flanges being substantially rigid and arranged to grip a rail base by skewing the anchor horizontally, substantially as described.
- 10 9. A rail anchor, comprising a base portion having an upwardly extending flange at each end, each of said flanges having an approximately vertical rail gripping face, the two rail gripping faces being at different 15 heights from said base, each of said flanges terminating at its upper end above the rail gripping face in an inwardly projecting lip, and the flange having the rail gripping face at the higher level also having a laterally 20 extending recess below said face, said base and flanges being substantially rigid and arranged to grip a rail base by skewing the anchor horizontally, substantially as described.
- 25 10. A rail anchor comprising a yoke formed with jaws adapted to grip opposite edges of a rail base and formed with a recess which normally extends beyond one of the vertical edges of the rail base and is 30 adapted to receive one edge of the rail base during the application of the device to the rail.
11. A rail anchor comprising a yoke which normally extends diagonally across 35 the bottom of the rail and is formed with
- jaws adapted to grip opposite edges of a rail base at points longitudinally remote from each other and formed with a recess adjacent one of said jaws adapted to receive one edge of the rail base during the application 40 of the device to the rail.
12. A rail anchor comprising a yoke member which extends under a rail base and normally out of engagement therewith, jaw portions having lips adapted to extend over 45 the upper surface of the rail base, and a spring element for maintaining the anchor in operative position.
13. A rail anchor comprising a yoke member which extends under a rail base and normally out of engagement therewith, jaw portions having lips adapted to extend over 50 the upper surface of the rail base, and a spring element interposed between the yoke and rail base for maintaining the anchor in 55 operative position.
14. A rail anchor comprising a yoke member which extends under a rail base and normally out of engagement therewith, jaw portions having lips adapted to extend over 60 the upper surface of the rail base, and a spring element interposed between the yoke and rail base for maintaining a frictional engagement between the upper surface of the rail base and said lips whereby the anchor is held in operative position. 65

In testimony whereof I have hereunto set my hand.

LAURENCE J. BERKELEY.
